Primary Examiner — Christy Nemeth

(57) **CLAIM**

The ornamental design for a charging box, as shown and described.

DESCRIPTION

FIG. 1 is a top plan view of a charging box showing my new design in an open state;

FIG. 2 is a top, front and left side perspective view thereof;

FIG. 3 is a top, front and right side perspective view thereof;

FIG. 4 is a bottom, rear and left side perspective view thereof;

FIG. 5 is a bottom, rear and right side perspective view thereof;

FIG. 6 is a top, front and right side perspective view showing the charging box in a closed state; and,

FIG. 7 is a top, rear left side perspective view of FIG. 6. The broken lines in the drawings illustrate portions of the charging box which form no part of the claimed design.

1 Claim, 7 Drawing Sheets
